UNITED STATES PATENT OFFICE

2,523,881

DRAIN CONNECTOR FOR DOWNSPOUTS

James W. Shea, Detroit, Mich.

Application August 28, 1948, Serial No. 46,593

3 Claims. (Cl. 210—170)

1

This invention relates to an improved drain connector for a downspout.

Downspouts which lead from the eave troughs of a building are generally led into a fixed drain in the ground and connected thereto by cement or in some other permanent fashion. It is common to provide a screen in the upper end of the downspout to keep leaves or other refuse from clogging the same. This practice is quite common, but a disadvantage of such a construction is that the leaves and other material collect in the eave troughs and have to be cleaned out at intervals which is a troublesome job.

An object of this invention is to provide a downspout connector which constitutes a removable section that is adapted to have its upper end detachably coupled with the lower end of a downspout and have its bottom end detachably coupled with the upper open end of a drain.

This improved connector is so constructed that it is adapted to form a suitable connection between the lower end of the downspout and the upper end of the drain even though such parts are offset somewhat with respect to each other. It is also so constructed that its lower end is adapted to be coupled with drain openings of somewhat different sizes. A further meritorious feature is that the connector is built up of a minimum number of readily detachable parts which are simple and inexpensive and which are easily disassembled to permit cleaning.

This improved connector includes a strainer and is adapted to strain the leaves and other foul material from the water travelling therethrough and such foul material can be quickly removed from the connector whenever the same becomes clogged.

Other objects, advantages and meritorious features will more fully appear from the following description, claims and accompanying drawings, wherein:

Fig. 1 is a vertical sectional view through a drain and downspout showing my improved connector partly in elevation and partly in section therebetween.

Fig. 2 is a transverse sectional view taken on the line 2—2 of Fig. 1.

Fig. 3 is a vertical sectional view taken on the same line as Fig. 1 through a drain showing a slight modification.

Fig. 4 is a fragmentary perspective illustrating a modification.

In the drawing a conventional drain crock is indicated at 10. This crock has a bell-mouth upper portion 12 which projects above the ground as

shown. A downspout is indicated as 14. My connector comprises a piece of flexible tubing indicated generally at 16. It may be the conventional flexible tubing of commerce. It is of a size to telescope over the downspout 14 and a set screw 18 might be provided to detachably secure it to the downspout. At the lower end, this flexible tubing is adapted to be received within the opening in a coverplate 20. This coverplate is shown in Figs. 1, 2 and 3 as a circular plate which is upwardly convex and provided with an opening therein through which my connector projects. This opening is flanged as at 22 to provide a seat that is adapted to support a strainer 24.

The strainer is a cup-shaped strainer and comprises a screen carried by a band portion which seats upon the flange 22 and itself receives the lower end of the connector as shown in Figs. 1 and 3. The connector is removably received within the strainer. The strainer is removably seated within the opening in the coverplate.

The coverplate is made of a size to fit over a crock such as 10 or over a cast iron drain such as 26 shown in Fig. 3. The cast iron drain 26 is of a different diameter from the crock 10. The coverplate is provided with a series of apertures 28 adapted to receive positioning pins or screws 30 as shown in Figs. 2 and 3 which screws are adapted to position the plate within the crock. A plurality of series of pin apertures 28 are provided spaced different distances from the periphery of the plate so that the pins 30 may be received therethrough to position the plate upon a large diameter crock or a smaller diameter drain.

In Fig. 4, I illustrate a modified type of construction. The drain is indicated as 26. It has a bell-mouth 27. The coverplate is of a modified form and is here indicated as 32. It is provided with an opening 34 adapted to receive a strainer such as 24 and to receive the lower end of the connector 16. This coverplate is upwardly dished, but instead of having locating pins and apertures as described hereinabove, the periphery of the coverplate is provided with a series of incisions 36. These incisions extend radially. They define lugs or tangs 38 which are capable of being bent downwardly out of the plane of the coverplate to engage over the upper margin of the drain as shown in Fig. 4.

The coverplate would be formed of metal sufficiently thin so that these lugs might be readily bent by the user. The incisions extend radially to such a depth that the lugs may be bent so as

to engage over the margins of drains of different diameter. If the coverplate were used with a large diameter drain such as the bell-mouth 12 of the drain 10, the lugs 38 might even be bent downwardly to be received within the interior of the bell-mouth much as the pins 30 are shown to be in Fig. 1 instead of being bent to grip the outer surface of the drain.

As a supplemental strainer there is provided a second screen element 40 which is shown in Figs. 1 and 2 as seated within the bell-mouth of the drain elements.

The flexible character of the tube 16 enables the tube to be bent in order to be connected to a downspout 14 which extends at an angle or does not directly overlie the drain crock 10, or to a drain crock which extends at an inclination to the vertical rather than in the upright position as shown.

What I claim is:

1. A drain connector for a downspout comprising, in combination, a length of flexible tubing having means at its upper end adapted to removably connect the same with the downspout over which it is telescoped, an upwardly convex plate adapted to cover the open end of the drain, means carried by the plate adapted to position the same over the open end of the drain, said plate provided with an opening of sufficient size to receive the end of the flexible tubing therethrough from the top and a downwardly convex strainer receivable from the top through the opening of the plate and removably seated therein below the end of the flexible tubing.

2. A drain connector for a downspout comprising, in combination, a length of flexible tubing having means at its upper end adapted to removably connect the same with the downspout over which it is telescoped, a circular plate adapted to cover the open end of the drain, means car-

ried by the plate adapted to position the same over the open end of the drain, said plate provided with an opening of sufficient size to receive the end of the flexible tubing therethrough and a cup-shaped strainer receivable through the opening in the plate and removably seated therein, said strainer adapted to removably receive the lower end of the flexible tubing therein.

3. A drain connector for a downspout comprising, in combination, a length of flexible tubing adapted at its upper end to be removably connected with the downspout, an upwardly convex plate adapted to cover the open end of the drain, the periphery of said plate being provided with a plurality of circumferentially spaced slits forming fingers adapted to be bent out of the plane of the plate to engage the periphery of the drain either inside or outside, said plate provided with an opening for the lower end of the flexible tubing, a cup-shaped strainer removably seated within said opening, the lower end of the flexible tubing projecting through said opening and removably seated within the cup-shaped strainer.
